ATTORNEY

UNITED STATES PATENT OFFICE.

EMIL GORNICEC, OF YOUNGSTOWN, OHIO.

PADLOCK.

Application filed April 4, 1927. Serial No. 180,957.

The objects of the invention are to provide a keyless padlock in which the protruding shackle or link is locked from movement by means of a sliding latch which engages 5 with one arm of the shackle and which can only be released by the interposition of a rolling ball between movable parts, the function of which is to complete the connection of the parts in such a manner that by means of 10 a slight movement of the other arm of the shackle, the sliding latch can be released from engagement with the arm of the shackle arm to permit this arm to be withdrawn from the case. 15 The invention comprises, a casing in which the shackle is inserted, one arm of the shackle being pivoted therein and having a yielding pivotal joint, a rock arm operable by pushing the pivoted arm inwardly when the ball is 20 interposed therebetween and a latch bar slideable in the casing and engageable with the other arm of the shackle, said bar being operatively connected with said rock arm so that when the ball is interposed and the rock 25 arm is depressed the latch bar will be released from the shackle.

Also a labyrinth passage is provided within the casing which must be traversed by the ball before it can enter between the pivoted arm of the shackle and the rock arm to make the arm operative. This passage differs in shape in different locks and its structure and ramifications must be familiar to the owner 30 of the lock before the ball can be positioned 35 in operative position between the pivoted arm of the shackle and the rock arm, hence making it impossible for one unacquainted with its construction to open the lock.

The invention is hereinafter described, 40 illustrated in the accompanying drawings and specifically pointed out in the claims.

In the accompanying drawings, Figure 1 is a plan of the lock with the cover removed showing the device in the locked position. 45 Figure 2 is a transverse section of cover and casing. Figure 3 is a plan showing the device unlocked and the sliding latch bar released by the interposition of a ball between the pivoted end of the shackle and the rock arm. Figure 4 is a perspective of the sliding latch. Fig. 5 is a plan of a modified form of lock. In these figures A represents the casing of the lock, B represents the loop of the shackle, one arm C of the shackle being pivoted upon a pin D in the casing and 50 yieldingly depressible by means of the slotted 55

journal opening E in which the pin projects and a coiled spring F therein. The other arm G of the shackle is provided with a shoulder H normally engaged with a latch 60 bar I slidably movable between a rectilinear guide shoulder J and guide pins or lugs J' and is operated to release the shackle by means of a rock arm K pivoted at L in the casing and engaged at M' with the latch bar. 65 The pivoted end C of the hasp and the adjacent edge O of the rock arm are separated normally, by an inclined channel P but when a ball Q is caused to roll between these opposed surfaces a downward pressure upon 70 the pivoted side of the shackle will cause the ball to press against the side of the rock arm, and the latch bar will be withdrawn from the shoulder thus releasing the shackle. To make the positioning of the ball in the channel difficult to obtain so that only one familiar with the structure of the lock can operate it, a labyrinth is formed of walls of irregular shape, at R, S, and T so positioned 75 that channels U, V, W, and X are formed 80 between them which the ball must follow correctly before it can enter the channel P, which is accomplished by first tilting the ball to the left until it is stopped by the notch X in the wall of the casing and stopped 85 from entering a pocket Z in the labyrinth. Then the casing is tilted to the right until the ball passes into the channel P.

I do not, however, confine the shape of the walls or channels to any one design but any 90 tortuous channel suitable to form a confusing labyrinth is within the scope of the invention and following claims.

A cover A' is pressed into a dovetail shoulder A'' in the edge of the casing A. 95

In Fig. 5 a similar device is shown, with the exception that the hasp B is not pivoted but moves longitudinally in the casing and when released is thrown outward by means of a spring B'.

Also a pivoted detent B² locks the rock arm K when the hasp is pushed in to operate the rock arm and latch bar K.

This construction is useful since the latch bar will remain withdrawn until the arm B³ 105 on the detent is struck by a shoulder B⁴ on the shackle.

Having described the invention what I claim as new and desire to secure by Letters Patent is:

1. In a keyless padlock, in combination, a casing, a shackle loop having one arm pivoted

- and longitudinally depressible in the wall of said casing, the other arm being provided with a retaining shoulder adjacent to its extremity, a latch member movable in said casing and engageable with said shoulder to retain the same, a movable operating member for said latch member, and a ball interposable between said pivoted arm of said shackle and said latch operating member.
10. 2. In a keyless padlock, in combination, a casing, a shackle loop having one arm pivoted and longitudinally depressible in the wall of said casing, the other arm being provided with a retaining shoulder adjacent to its extremity, a latch member movable in said casing and engageable with said shoulder to retain the same, a movable operating member for said latch member, and a ball interposable between said pivoted arm of said shackle and said latch operating member and a labyrinthine passage or channel, in said casing leading to a position between said pivoted shackle arm and said latch operating member.
15. 3. In a keyless padlock, a casing, a shackle loop having a spring pressed arm pivoted and depressible in said casing, the other arm being provided with a locking shoulder, a latch bar slideable in said casing into and out of engagement with said shoulder, a rocking member for operating said latch bar, there being a channel separating said rocking member from the inner extremity of said pivoted shackle arm, a ball in said casing movable into said channel to cause an inward movement of said arm to operate said rocking member and release said latch.
20. 4. In a keyless padlock, a casing, a shackle loop having a spring pressed arm pivoted and depressible in said casing, the other arm being provided with a locking shoulder, a latch bar slideable in said casing into and out of engagement with said shoulder, a rocking member for operating said latch bar, there being a channel separating said rocking member from the inner extremity of said pivoted shackle arm, a ball in said casing movable into said channel to cause an inward movement of said arm to operate said rocking member and release said latch and labyrinthine walls in said casing forming circuitous channels that must be traversed by said ball before it can enter
5. In a keyless padlock, a casing, a shackle loop having a spring pressed arm pivoted and depressible in said casing, the other arm being provided with a locking shoulder, a latch bar slideable in said casing into and out of engagement with said shoulder, a rocking member for operating said latch bar, there being a channel separating said rocking member from the inner extremity of said pivoted shackle arm, a ball in said casing movable into said channel to cause an inward movement of said arm to operate said rocking member and release said latch and labyrinthine walls in said casing forming circuitous channels that must be traversed by said ball before it can enter
65. 6. In a keyless padlock, a casing, a shackle, having a latching shoulder at one end and having one arm longer than the other and longitudinally movable in said lock, a transversely movable latch engageable with said shoulder and an operating member therefor spaced from the longer end of said shackle and a ball loose in said casing which when interposed between said longer end of said shackle and said operating member, will cause said member to release said latch on the inward movement of said shackle.
70. 7. In a keyless padlock, a casing, a shackle, having a latching shoulder at one end and having one arm longer than the other and longitudinally movable in said lock, a transversely movable latch engageable with said shoulder and an operating member therefor spaced from the longer end of said shackle and a ball loose in said casing which when interposed between said longer end of said shackle and said operating member, will cause said member to release said latch on the inward movement of said shackle and a return spring
75. 80. 85. 90. 95. 100.

In testimony whereof I affix my signature.

EMIL GORNICEC.
